UNITED STATES PATENT OFFICE.

WILLIAM J. VALELLY, OF BONHAM, TEXAS.

MEANS FOR REMOVING GRASS FROM RAILROAD TRACKS

Application filed November 1, 1927. Serial No. 230,345.

This invention is a device for destroying grass and weeds in railroad tracks and its object is to provide a simple attachment which may be readily secured to any railroad car truck and operated by the wheels of the truck to cut down all the grass and other vegetable growth between the track rails and immediately adjacent the same. It is well known that grass and weeds growing in a railroad track will spread over the track rails and be crushed thereon so that the rails become slippery and the locomotive fails to obtain sufficient traction to draw its load. By the use of my invention, the grass and weeds are destroyed and, consequently, the slippery condition of the track rails is avoided. The invention is illustrated in the accompanying drawing and will be hereinafter fully set forth and particularly defined.

20 In the drawing:

Figure 1 is an elevation of a portion of a car truck having my attachment applied thereto;

Fig. 2 is a top plan view of the same;

25 Fig. 3 is an enlarged detail section on the line 3-3 of Fig. 2;

Fig. 4 is an enlarged detail section on the line 4-4 of Fig. 2, and

Fig. 5 is a section on the line 5—5 of Fig. 4.

30 The car truck, a portion of which is shown at 1, may be of any approved construction, and usually the attachment is applied to one of the trucks of the locomotive tender. In carrying out the invention, I provide supporting arms consisting of a lower strap bar 2 and an upper strap bar 3 which are connected at their outer ends by a bridge member 4 which may be cast or otherwise formed integral with the strap bars. The opposite

40 ends of the bars are disposed respectively below and above the journal box 5 of the car truck and are firmly secured thereto by bolts 6 inserted through the bars at the sides of the journal box, as will be understood upon reference to Fig. 1. It will be understood, however, that the strap bars need not be applied to the journal boxes of the truck but may be secured to the side beams or other fixed members of the truck. Between the

fixed members of the truck. Between the strap bars 2 and 3, bearing boxes or blocks 7 are fitted, and these blocks or boxes are provided upon their tops and bottoms with parallel vertical flanges 8 between which the strap bars are received, as shown clearly in Fig. 3, so that the boxes or blocks will be prevented from having lateral movement.

with respect to the strap bars. The boxes or blocks may slide along the strap bars and are yieldably held toward the truck by expansion springs 9 disposed between the strap bars and bearing at one end against the boxes and at their opposite ends against abutments 10 carried by adjusting screws 11 mounted in the bridging members 4, as shown and as will be understood. The boxes 7 receive the outer ends of a shaft 12 which extends from box to box and has its ends fitted within thimbles or bushings 13 pressed into the boxes so as to minimize wear, and oil cups 14 are also carried by the boxes to deliver oil to the journals of the shaft in order that the shaft may run easily and freely at all times. Secured to the shaft are a plurality of stiff brushes 15 which are preferably composed of bunches of wire strands and are provided in such number as to extend across the entire space between the track rails and also operate at the outer sides of the rails, as will be understood upon reference to Fig. 2. Adjacent the ends of the shaft 12, friction disks 16 are secured thereon, and these disks are so arranged as to bear against the treads of the car wheels 17 so as to receive motion therefrom, it being seen at once that the brushes will rotate reversely to the wheels so that they will effectually sweep over the track bed and cut away the obnoxious vegetable growth. The friction disks are preferably constructed of fiber or have their peripheries covered with leather so as to obtain the desired good frictional contact with the car wheels and they are held yieldably to the car wheels by the springs 9 in an obvious manner, the adjusting screws 11 providing for the adjustment of the shaft to obtain the proper degree of friction and to compensate for wear. In order to maintain the strap bars 2 and 3 in the proper parallel relation and prevent bending of the same so as to interfere with the proper yielding movement of the boxes a filler 18 is provided between and secured to the bars, as shown clearly in Fig. 1, between the boxes 7 and the car truck. It will also be noted that the lower strap bar 2 extends in a single horizontal plane while the upper bar is offset both vertically and horizontally, as at 19, in order to locate the brush shaft 12 at a low point and accommodate brushes at the outer side of the track rail and the filler block is located immediately in advance of the bend in the upper bar.

While the brushes may be secured to the

brush shaft in various ways, I have shown an efficient method which I prefer. A circumferentially extending recess or notch 20 is provided in the brush shaft in which the brush may seat tangentially to the shaft, and a clamping plate 21 is disposed against the outer side of the brush, said plate having a groove 22 therein to fit around the brush. The groove and notch may have a radius sufficient to completely encircle the brush, or the brush fibers may be tied together between their ends. A U-bolt 23 is fitted over the shaft and through diagonally opposite corners of the plate 21, and nuts 24 on the ends of the bolt are turned home against the plate to securely clamp the brush to the shaft. When the brush wears, loosening of the nuts will permit it to be adjusted to take up the wear and then be again secured, and practically half the length of the brush is thus available for effective use.

The action of the device will be readily understood. The attachment is applied to the truck and properly adjusted so that the friction disks will be in contact with the car wheels, whereupon whenever the car is in motion the brush shaft 12 will be rotated and the brushes caused to sweep through the vegetation and cut down the same. The brushes should be of such length that they will sweep close to the roots of the growth and in many instances will uproot the same so that the growth will be entirely destroyed. The device is exceedingly simple in the construction and arrangement of its parts and may be easily applied to any car truck. It does not add perceptibly to the draft or load of the car and is not apt to get out of order so that after being applied it requires little, if any attention.

Having thus described the invention, I claim:

1. A device for the purpose set forth com-

prising attaching arms, means for securing said arms to a car truck, a brush shaft carried by said arms, brushes secured to said shaft, friction disks secured on said shaft and adapted to be rotated by the wheels of a car truck, and means carried by the arms for holding the friction disks to the car wheels. 45 50

2. A device for the purpose set forth comprising a pair of arms, means for attaching the arms to a car truck, boxes slidably fitted in said arms, a shaft extending between and carried by said boxes, brushes secured to said shaft, friction disks secured on said shaft and adapted to engage the wheels of a car truck, expansion springs carried by the arms and bearing against the boxes to yieldably hold the disks to the car wheels, and means 55 60 65 for adjusting the tension of the springs.

3. A device for the purpose set forth comprising upper and lower strap bars disposed in vertically spaced relation, both bars being laterally offset and the upper bars being vertically offset, means for securing the rear ends of said bars to a car truck, boxes slidably mounted between and carried by said bars, thimbles fitted in said boxes, a shaft having its ends journaled in said thimbles, 70 75 brushes secured to said shaft, friction disks secured on said shaft and adapted to engage the wheels of a car truck, and means carried by the outer ends of the strap bars to yieldably hold the disks to the car wheels.

4. A device for the purpose set forth comprising supporting arms, a shaft supported by and between said arms, a brush disposed tangentially against the shaft, a clamping plate bearing against the brush, a U-bolt fitted over the shaft and through the plate, and securing nuts on the bolt turned home against the plate whereby to clamp the brush to the shaft.

In testimony whereof I affix my signature.

WILLIAM J. VALELLY. [L. S.]
